A common-mode choke coil includes a multilayer body, a first coil, a second coil, a first terminal electrode, a second terminal electrode, a third terminal electrode, and a fourth terminal electrode. The multilayer body includes plural non-conductor layers. The first and second coils are incorporated in the multilayer body. The first and second terminal electrodes are connected to the first coil. The third and fourth terminal electrodes are connected to the second coil. The first coil has a path length L1, the second coil has a path length L2, and the sum of the path length L1 and the path length L2 is less than or equal to 3.5 mm. The non-conductor layers each have a relative permittivity of less than or equal to 11.

COMMON-MODE CHOKE COIL

CROSS-REFERENCE TO RELATED APPLICATION

This application claims benefit of priority to Japanese Patent Application No. 2020-132930, filed Aug. 5, 2020, the entire content of which is incorporated herein by reference.

BACKGROUND

Technical Field

The present disclosure relates to a common-mode choke coil. More specifically, the present disclosure relates to a multilayer common-mode choke coil including a multilayer body with plural stacked non-conductor layers, and a first coil and a second coil that are incorporated in the multilayer body.

Background Art

A technique that is of interest for the present disclosure is described in, for example, Japanese Unexamined Patent Application Publication No. 2006-313946. The technique described in Japanese Unexamined Patent Application Publication No. 2006-313946 relates to a multilayer common-mode choke coil. The common-mode choke coil is an ultra-small thin-film common-mode choke coil, and capable of high-speed transmission of transmission signals at frequencies near the GHz range. More specifically, Japanese Unexamined Patent Application Publication No. 2006-313946 describes a common-mode choke coil with a cutoff frequency of greater than or equal to 2.4 GHz, the cutoff frequency being defined as the frequency at which the attenuation of a transmission signal (differential-mode signal) reaches -3 dB.

Advances in high-speed communication technology have led to the growing need for a multilayer common-mode choke coil that can, at increasingly higher frequencies, transmit differential-mode signals and suppress common-mode noise components.

SUMMARY

Accordingly, the present disclosure provides a multilayer common-mode choke coil that can, at higher frequencies such as 25 GHz to 30 GHz, and even at very high frequencies such as above 30 GHz, transmit differential-mode signals, and suppress common-mode noise components.

A common-mode choke coil according to preferred embodiments of the present disclosure includes a multilayer body, a first coil, a second coil, a first terminal electrode, a second terminal electrode, a third terminal electrode, and a fourth terminal electrode. The multilayer body includes a plurality of non-conductor layers, the plurality of non-conductor layers being stacked and each made of a non-conductor. The first coil and the second coil are incorporated in the multilayer body. The first terminal electrode and the second terminal electrode are provided on an outer surface of the multilayer body, the first terminal electrode being electrically connected to a first end, the second terminal electrode being electrically connected to a second end, the first end and the second end being different ends of the first coil. The third terminal electrode and the fourth terminal electrode are provided on an outer surface of the multilayer body, the third terminal electrode being electrically con-

2

nected to a third end, the fourth terminal electrode being electrically connected to a fourth end, the third end and the fourth end being different ends of the second coil.

The plurality of non-conductor layers include a first plurality of non-conductor layers and a second plurality of non-conductor layers. The first coil includes a first coil conductor disposed along a first interface, the first interface being an interface between the first plurality of non-conductor layers. The second coil includes a second coil conductor disposed along a second interface, the second interface being an interface between the second plurality of non-conductor layers and different from the first interface along which the first coil conductor is disposed.

To address the above-mentioned technical problem, preferred embodiments of the present disclosure have a first characteristic feature and a second characteristic feature. According to the first characteristic feature, the first coil has a path length L1, the second coil has a path length L2, and the sum of the path lengths L1 and L2 is less than or equal to 3.5 mm. According to the second characteristic feature, the plurality of non-conductor layers each have a relative permittivity of less than or equal to 11.

According to preferred embodiments of the present disclosure, the stray capacitance between the first coil and the second coil can be reduced. In particular, attenuation of differential-mode components, which are signal components, at frequencies from, for example, 20 GHz to 40 GHz can be reduced. This helps to improve the high-frequency characteristics of the common-mode choke coil.

Other features, elements, characteristics and advantages of the present disclosure will become more apparent from the following detailed description of preferred embodiments of the present disclosure with reference to the attached drawings.

BRIEF DESCRIPTION OF THE DRAWINGS

FIG. 1 is a perspective view of a common-mode choke coil according to an embodiment of the present disclosure, illustrating the outward appearance of the common-mode choke coil;

FIG. 2 is an exploded plan view of the major components of the common-mode choke coil illustrated in FIG. 1;

FIG. 3 is a plan view of the common-mode choke coil illustrated in FIG. 1, representing a schematic see-through illustration of first and second coils incorporated in a multilayer body as viewed in the stacking direction;

FIG. 4 is a plan view of a first coil conductor included in the first coil of the common-mode choke coil illustrated in FIG. 1, explaining the number of turns of the first coil conductor;

FIG. 5 is a schematic cross-sectional view, taken along a line A-A in FIG. 1, of a common-mode choke coil corresponding to Sample 9, which is one representative example of common-mode choke coil samples fabricated in an exemplary experiment conducted to verify the effects of the present disclosure;

FIG. 6 illustrates the transmission characteristic for common-mode components (Scc21 transmission characteristic) obtained for a common-mode choke coil corresponding to Sample 8 among the common-mode choke coil samples fabricated in the exemplary experiment; and

FIG. 7 illustrates the transmission characteristic for differential-mode components (Sdd21 transmission characteristic) obtained for the common-mode choke coil corresponding to Sample 8.

DETAILED DESCRIPTION

With reference to FIGS. 1 through 4, a common-mode choke coil 1 according to an embodiment of the present disclosure is described below.

As illustrated in FIG. 1, the common-mode choke coil 1 includes a multilayer body 2 having plural stacked non-conductor layers. FIG. 2 depicts representative non-conductor layers 3a, 3b, 3c, 3d, and 3e among these non-conductor layers. In the following description, unless individual non-conductor layers are to be distinguished from each other such as in the case of the non-conductor layers 3a, 3b, 3c, 3d, and 3e illustrated in FIG. 2, reference sign "3" is used for non-conductor layers to generically describe each non-conductor layer. Each non-conductor layer 3 is made of a non-conductor, examples of which include glass and ceramic materials.

The multilayer body 2 is substantially a cuboid in shape that has a first major face 5, a second major face 6, a first lateral face 7, a second lateral face 8, a first end face 9, and a second end face 10. The first major face 5 and the second major face 6 extend in a direction in which the non-conductor layers 3 extend, and are opposite to each other. The first lateral face 7 and the second lateral face 8 couple the first major face 5 and the second major face 6 to each other, and are opposite to each other. The first end face 9 and the second end face 10 couple the first major face 5 and the second major face 6 to each other, and couple the first lateral face 7 and the second lateral face 8 to each other. The first end face 9 and the second end face 10 are opposite to each other. The cuboid may be, for example, rounded or chamfered in its edge and corner portions.

As illustrated in FIGS. 2 and 3, the common-mode choke coil 1 includes a first coil 11 and a second coil 12 that are incorporated in the multilayer body 2. As illustrated in FIG. 1, the common-mode choke coil 1 also includes the following terminal electrodes provided on the outer surface of the multilayer body 2: a first terminal electrode 13, a second terminal electrode 14, a third terminal electrode 15, and a fourth terminal electrode 16. More specifically, the first terminal electrode 13 and the third terminal electrode 15 are provided on the first lateral face 7, and the second terminal electrode 14 and the fourth terminal electrode 16, which are respectively symmetrical in shape to the first terminal electrode 13 and the third terminal electrode 15, are provided on the second lateral face 8.

As illustrated in FIG. 2, the first terminal electrode 13 and the second terminal electrode 14 are respectively electrically connected to a first end 11a and a second end 11b, which are different ends of the first coil 11. The third terminal electrode 15 and the fourth terminal electrode 16 are respectively electrically connected to a third end 12a and a fourth end 12b, which are different ends of the second coil 12.

The following description assumes that the non-conductor layers 3a, 3b, 3c, 3d, and 3e are stacked from the bottom to the top in the order depicted in FIG. 2.

Referring to FIG. 2, the first coil 11 has a first coil conductor 17 disposed along the interface between the non-conductor layers 3b and 3c. The first coil 11 has a first extended conductor 19, and a second extended conductor 20. The first extended conductor 19 provides the first coil 11 with the first end 11a. The second extended conductor 20 provides the first coil 11 with the second end 11b. The first extended conductor 19 includes a first connection end portion 23. The first connection end portion 23 is connected to the first terminal electrode 13 at a location on the outer surface of the multilayer body 2. The second extended

conductor 20 includes a second connection end portion 24. The second connection end portion 24 is connected to the second terminal electrode 14 at a location on the outer surface of the multilayer body 2.

5 The first connection end portion 23 is disposed along the interface between the non-conductor layers 3a and 3b different from the interface between the non-conductor layers 3b and 3c along which the first coil conductor 17 is disposed. The first extended conductor 19 includes a first via-conductor 27, and a first coupling part 29. The first via-conductor 27 is connected to the first coil conductor 17, and penetrates the non-conductor layer 3b, which is located between the first coil conductor 17 and the first connection end portion 23, in the thickness direction of the non-conductor layer 3b. 10 The first coupling part 29 is disposed along the interface between the non-conductor layers 3a and 3b along which the first connection end portion 23 is disposed. The first coupling part 29 connects the first via-conductor 27 and the first connection end portion 23 to each other. The first coupling part 29 is preferably shaped to extend substantially linearly. 15 As a result, an inductance due to the first coupling part 29 can be reduced, and high-frequency characteristics can be thus improved.

20 As described below, the second coil 12 also has elements similar to those of the first coil 11.

The second coil 12 includes a second coil conductor 18 disposed along the interface between the non-conductor layers 3c and 3d. The second coil 12 includes a third extended conductor 21, and a fourth extended conductor 22. 25 The third extended conductor 21 provides the second coil 12 with the third end 12a. The fourth extended conductor 22 provides the second coil 12 with the fourth end 12b. The third extended conductor 21 includes a third connection end portion 25. The third connection end portion 25 is connected to the third terminal electrode 15 at a location on the outer surface of the multilayer body 2. The fourth extended conductor 22 includes a fourth connection end portion 26. The fourth connection end portion 26 is connected to the fourth terminal electrode 16 at a location on the outer surface 30 of the multilayer body 2.

The third connection end portion 25 is disposed along the interface between the non-conductor layers 3d and 3e different from the interface between the non-conductor layers 3c and 3d along which the second coil conductor 18 is disposed. The third extended conductor 21 includes a second via-conductor 28, and a second coupling part 30. The second via-conductor 28 is connected to the second coil conductor 18, and penetrates the non-conductor layer 3d, which is located between the second coil conductor 18 and the third connection end portion 25, in the thickness direction of the non-conductor layer 3d. The second coupling part 30 is disposed along the interface between the non-conductor layers 3d and 3e along which the third connection end portion 25 is disposed. The second coupling part 30 connects the second via-conductor 28 and the third connection end portion 25 to each other. As with the first coupling part 29 mentioned above, the second coupling part 30 is preferably shaped to extend substantially linearly. As a result, an inductance due to the second coupling part 30 can be reduced, and high-frequency characteristics can be thus improved.

60 The common-mode choke coil 1 is mounted with the second major face 6 of the multilayer body 2 directed toward a mounting substrate. In one exemplary embodiment of the common-mode choke coil 1, the multilayer body 2 has a length dimension L of greater than or equal to about 0.55 mm and less than or equal to about 0.75 mm (i.e., from about

0.55 mm to about 0.75 mm), which is defined between the first and second end faces **9** and **10** that are opposite to each other, a width dimension **W** of greater than or equal to about 0.40 mm and less than or equal to about 0.60 mm (i.e., from about 0.40 mm to about 0.60 mm), which is defined between the first and second lateral faces **7** and **8** that are opposite to each other, and a height dimension **H** of greater than or equal to about 0.20 mm and less than or equal to about 0.40 mm (i.e., from about 0.20 mm to about 0.40 mm), which is defined between the first and second major faces **5** and **6** that are opposite to each other.

As is apparent from FIGS. 2 and 3, the first and second coil conductors **17** and **18** of the common-mode choke coil **1** each preferably have a number of turns of less than about 2.

The number of turns mentioned above is defined as follows. The first coil conductor **17** and the second coil conductor **18** each have a portion that extends in a substantially arcuate shape. Referring now to FIG. 4, the first coil conductor **17** of the first coil **11** is described below. As illustrated in FIG. 4, a tangent **T** is drawn sequentially along the outer periphery of the coil conductor **17** from the beginning end of the coil conductor **17** to the terminating end, and when the tangent **T** has rotated 360 degrees, this is defined as one turn. For the coil conductor **17** illustrated in FIG. 4, the tangent **T** has rotated approximately 307 degrees, and hence the number of turns of the coil conductor **17** can be defined as approximately 0.85. The number of turns is defined in the same manner also for the second coil conductor **18** of the second coil **12**.

The smaller the number of turns of the first coil conductor **17** and the number of turns of the second coil conductor **18**, the more the stray capacitance generated between the first coil **11** and the second coil **12** can be reduced. Hence, a smaller number of turns allows for improved high-frequency characteristics of the common-mode choke coil **1**.

In connection with the relatively small number of turns of each coil conductor, a first characteristic feature of the common-mode choke coil **1** resides in that the sum of path lengths **L1** and **L2** is less than or equal to about 3.5 mm, the path length **L1** being the path length of the first coil **11**, the path length **L2** being the path length of the second coil **12**. Due to this characteristic feature, the stray capacitance generated between the first coil **11** and the second coil **12** can be reduced. This helps to ensure that, at high frequencies, the common-mode choke coil **1** can transmit differential-mode signals and suppress common-mode noise components, which allows for improved high-frequency characteristics of the common-mode choke coil **1**.

In FIG. 2, the path length **L1** of the first coil **11** is the total length of the path that extends from the first end **11a** of the first coil **11** to the second end **11b** via the following parts: the first connection end portion **23**, the first coupling part **29**, and the first via-conductor **27**, which are included in the first extended conductor **19**; and the second connection end portion **24**, which is included in the second extended conductor **20**. For the first coil conductor **17**, the path length is measured along a substantially central portion in the width direction.

Likewise, in FIG. 2, the path length **L2** of the second coil **12** is the total length of the path that extends from the third end **12a** of the second coil **12** to the fourth end **12b** via the following parts: the third connection end portion **25**, the second coupling part **30**, and the second via-conductor **28**, which are included in the third extended conductor **21**; and the fourth connection end portion **26**, which is included in the fourth extended conductor **22**. For the second coil

conductor **18**, the path length is measured along a substantially central portion in the width direction.

In actuality, the above-mentioned path length measurement is performed as described below. First, the multilayer body **2** is ground in the stacking direction to expose the third connection end portion **25** and the second coupling part **30**. The path length of the third connection end portion **25**, and the path length of the second coupling part **30** are then measured with a measuring microscope. The grinding is further allowed to proceed to expose the second coil conductor **18** and the fourth connection end portion **26**, and the path length of the second coil conductor **18** and the path length of the fourth connection end portion **26** are then measured with the measuring microscope. The grinding is further allowed to proceed to expose the first coil conductor **17** and the second connection end portion **24**, and the path length of the first coil conductor **17** and the path length of the second connection end portion **24** are then measured with the measuring microscope. The grinding is further allowed to proceed to expose the first connection end portion **23** and the first coupling part **29**, and the path length of the first connection end portion **23** and the path length of the first coupling part **29** are then measured with the measuring microscope.

Meanwhile, another multilayer body **2** is prepared. The multilayer body **2** is ground in a direction orthogonal to the stacking direction of the multilayer body **2** to expose the first via-conductor **27** and the second via-conductor **28**. The respective lengths of the first and second via-conductors **27** and **28** in the stacking direction are then measured with the measuring microscope.

Subsequently, the sum of the lengths measured as mentioned above, that is, the length of the third connection end portion **25**, the length of the second coupling part **30**, the length of the second via-conductor **28**, the length of the second coil conductor **18**, and the length of the fourth connection end portion **26**, is found and taken as the path length of the second coil **12**. Likewise, the sum of the length of the first connection end portion **23**, the length of the first coupling part **29**, the length of the first via-conductor **27**, the length of the first coil conductor **17**, and the length of the second connection end portion **24** is found and taken as the path length of the first coil **11**.

Preferably, as clearly illustrated in FIG. 3, with the first coil conductor **17** and the second coil conductor **18** being viewed in plan in the stacking direction of the multilayer body **2**, the first coil conductor **17** and the second coil conductor **18** have no portion where the two coil conductors overlap each other, except for a portion where the two coil conductors cross each other. This also contributes to reducing the stray capacitance generated between the first coil **11** and the second coil **12**. As a result, the high-frequency characteristics of the common-mode choke coil **1** can be improved.

As is apparent from FIG. 3, with the first coil conductor **17** and the second coil conductor **18** being viewed in plan in the stacking direction of the multilayer body **2**, the first coil conductor **17** and the second coil conductor **18** cross each other at two locations. By ensuring that the first coil conductor **17** and the second coil conductor **18** cross each other at two or less locations in this way, the stray capacitance generated between the first coil conductor **17** and the second coil conductor **18** is reduced. This can contribute to improved high-frequency characteristics.

Preferably, the first coil conductor **17** and the second coil conductor **18** have a distance between each other of greater than or equal to about 6 μ m and less than or equal to about

26 μm (i.e., from about 6 μm to about 26 μm). If the above-mentioned distance is less than about 6 μm , this may cause the stray capacitance generated between the first coil conductor 17 and the second coil conductor 18 to become large enough to degrade high-frequency characteristics. By contrast, if the above-mentioned distance is greater than about 26 μm , this may cause a decrease in the coefficient of coupling between the first coil 11 and the second coil 12.

Although each of the non-conductor layers 3a, 3b, 3c, 3d, and 3e is depicted in FIG. 2 as being a single layer, at least some of these non-conductor layers may be made up of plural layers. Accordingly, for example, the above-mentioned distance between the first coil conductor 17 and the second coil conductor 18 may be adjusted either by changing the thickness of the non-conductor layer 3c formed as a single layer, or by changing the number of layers constituting the non-conductor layer 3c.

Preferably, each of the first coil conductor 17 and the second coil conductor 18 has a line width of greater than or equal to about 10 μm and less than or equal to about 24 μm (i.e., from about 10 μm to about 24 μm). If the line width is less than about 10 μm , this may cause the coil conductors 17 and 18 to have an increased direct-current resistance. By contrast, if the line width is greater than about 24 μm , this may cause the stray capacitance generated between the first coil conductor 17 and the second coil conductor 18 to become large enough to degrade high-frequency characteristics.

The terminal electrodes 13 to 16 extend over an area from the first major face 5 to the second major face 6. In this regard, each of the terminal electrodes 13 to 16 has a width on the first lateral face 7 or the second lateral face 8 (the width of the first terminal electrode 13 on the first lateral face 7 is denoted by "W1" in FIG. 1) of preferably greater than or equal to about 0.1 mm and less than or equal to about 0.25 mm (i.e., from about 0.1 mm to about 0.25 mm), more preferably greater than or equal to about 0.15 mm. If the above-mentioned width is less than about 0.1 mm, this may result in insufficient fixing strength when the common-mode choke coil 1 is mounted onto the mounting substrate. By contrast, if the above-mentioned width is greater than about 0.25 mm, this may lead to degradation of the high-frequency characteristics of the common-mode choke coil 1.

Each of the terminal electrodes 13 to 16 is depicted in FIG. 1 as being partially extended to the first major face 5. Although not depicted in FIG. 1, each of the terminal electrodes 13 to 16 is partially extended also to the second major face 6. Such an extended portion has a dimension E of preferably greater than or equal to about 0.02 mm and less than or equal to about 0.2 mm (i.e., from about 0.02 mm to about 0.2 mm), more preferably less than or equal to about 0.17 mm. A dimension E less than about 0.02 mm may cause a decrease in the strength with which the common-mode choke coil 1 is fixed to the mounting substrate when mounted onto the mounting substrate. By contrast, a dimension E greater than about 0.2 mm may lead to degradation of the high-frequency characteristics of the common-mode choke coil 1.

A second characteristic feature of the common-mode choke coil 1 resides in that each non-conductor layer 3 has a relative permittivity of less than or equal to about 11. As a result, the stray capacitance between the first coil 11 and the second coil 12 can be reduced. This helps to improve the high-frequency characteristics of the common-mode choke coil 1. In particular, with attention directed to differential-mode components, which are signal components, attenua-

tion of the differential-mode components at frequencies from, for example, 20 GHz to 40 GHz can be reduced.

Each non-conductor layer 3 has a relative permittivity of preferably less than or equal to about 7.9, more preferably less than or equal to about 6.0. This helps to ensure that the peak position of the transmission characteristic for common-mode components (Scc21 transmission characteristic) can be further shifted higher in frequency, and the transmission coefficient at the peak position can be further decreased.

As for the relative permittivity of each non-conductor layer 3, the lower the relative permittivity, the better. However, from the viewpoint of feasibility, the lower limit for the relative permittivity is set to about 3.0.

As described above, each non-conductor layer 3 preferably includes a glass-ceramic material. In this case, to further decrease relative permittivity, the relative permittivity of the non-conductor layer 3 is adjusted by, preferably, making the non-conductor layer 3 include a non-magnetic Zn—Cu ferrite in addition to the glass-ceramic material, or making the non-conductor layer 3 include voids.

FIG. 5 is a schematic cross-sectional view of the common-mode choke coil 1 corresponding to Sample 9 fabricated in an exemplary experiment described later. In FIG. 5, elements corresponding to the elements in FIGS. 1 through 3 are denoted by like reference signs. FIG. 5 depicts the common-mode choke coil 1 dotted with a large number of voids 33.

If each non-conductor layer 3 includes the voids 33, the volume fraction of the voids 33 in the non-conductor layer 3 is preferably less than or equal to about 30%.

Reference is now made to a preferred manufacturing method for the common-mode choke coil 1.

To fabricate a green sheet that is to become each non-conductor layer 3, a glass-ceramic material, a ferrite material, and a burn-out material are prepared as described below.

(1) Glass-Ceramic Material

To obtain a glass-ceramic material, K_2O , B_2O_3 , and SiO_2 , and as required, Al_2O_3 are weighed in predetermined proportions, put into a crucible made of platinum, and melted by being raised to a temperature of about 1500 to 1600°C. in a firing furnace. The resulting melted substance is rapidly cooled to yield a glass material.

An example of the above-mentioned glass material is a glass material containing at least K, B, and Si, with K contained at a K_2O equivalent of about 0.5 to 5 mass %, B at a B_2O_3 equivalent of about 10 to 25 mass %, Si at an SiO_2 equivalent of about 70 to 85 mass %, and Al at an Al_2O_3 equivalent of about 0 to 5 mass %.

Subsequently, the above-mentioned glass material is pulverized to obtain glass powder with a D50 particle size (particle size equivalent to 50% of the volume-based cumulative percentage) of about 1 to 3 μm .

Subsequently, alumina powder and quartz (SiO_2) powder both having a D50 particle size of about 0.5 to 2.0 μm are added to the above-mentioned glass powder. The resulting powder is put into a ball mill together with PSZ media, followed by wet mixing/pulverization. The resulting slurry is discharged from the ball mill, and then dried to thereby obtain a glass-ceramic material.

The glass-ceramic material contains, for example, about 60 to 66 mass % of glass material and, as fillers, about 34 to 37 mass % of quartz (SiO_2) and about 0.5 to 4 mass % of alumina.

(2) Ferrite Material

A ferrite material to be used is non-magnetic. To obtain such a ferrite material, Fe_2O_3 , ZnO , CuO , and as required, additives are weighed to achieve a predetermined composi-

tion, followed by mixing and pulverization. The pulverized ferrite material is dried, and then calcined at a temperature of, for example, about 700 to 800° C. to thereby obtain a ferrite material.

A suitable example of the above-mentioned ferrite material is a ferrite material containing, as its main components, about 40 to 49 mol % of Fe in terms of Fe_2O_3 , about 4 to 12 mol % of Cu in terms of CuO , and ZnO as the remainder, with trace additives (including incidental impurities) added to these main components.

(3) Burn-Out Material

A burn-out material is a material that combusts and burns out during firing. As such a burn-out material, for example, resin powder is used. More specifically, as the burn-out material, a burn-out material made of, for example, cross-linked polymethylmethacrylate, polystyrene, polyethylene, or polypropylene may be used. In particular, a burn-out material made of crosslinked polymethylmethacrylate is preferably used. The burn-out material used is substantially spherical in shape with a mean particle size in the range of about 1 to 8 μm , more preferably in the range of about 2 to 6 μm .

Subsequently, the glass-ceramic material and the ferrite material mentioned above are blended in predetermined proportions. Alternatively, the glass-ceramic material and the burn-out material are blended in predetermined proportions.

Subsequently, the above-mentioned blend is put into a ball mill together with PSZ media. Further, an organic binder such as a polyvinyl butyral-based organic binder, an organic solvent such as ethanol or toluene, and a plasticizer are put into the ball mill and mixed together to thereby obtain a glass-ceramic slurry.

Then, the glass-ceramic slurry is formed into a sheet with a film thickness of about 20 to 30 μm by a method such as the doctor blade method, and the obtained sheet is punched in a substantially rectangular shape. Plural green sheets are thus obtained.

Meanwhile, a conductive paste containing Ag as a conductive component and used for forming the first coil 11 and the second coil 12 is prepared.

Subsequently, a predetermined green sheet is subjected to, for example, irradiation with laser light to thereby provide the green sheet with a through-hole in which to place each of via-conductors 27 and 28. Then, the conductive paste is applied to the predetermined green sheet by, for example, screen printing. Thus, the via-conductors 27 and 28 with the conductive paste filling the above-mentioned through-hole are formed, and the coil conductors 17 and 18, the connection end portions 23 to 26 respectively constituting the extended conductors 19 to 22, and the coupling parts 29 and 30 are formed in a patterned state.

Subsequently, plural green sheets are stacked such that the non-conductor layers 3a to 3e stacked in the order illustrated in FIG. 2 can be obtained. At this time, on the top and bottom of the stack of these green sheets, a suitable number of green sheets with no through-hole provided therein and no conductive paste applied thereto are further stacked as required.

Subsequently, the stacked green sheets are subjected to thermocompression bonding to obtain a multilayer block.

Subsequently, the multilayer block is cut with a dicer or other device into individual discrete multilayer structures each dimensioned such that the multilayer structure can become the multilayer body 2 of each individual common-mode choke coil 1.

Subsequently, each discrete multilayer structure thus obtained is fired in a firing furnace at a temperature of about 860 to 900° C. for about 1 to 2 hours to thereby obtain the multilayer body 2.

5 The multilayer body 2 that has undergone firing, or each discrete multilayer structure that has not undergone firing yet is preferably placed into a rotating barrel together with media, and rotated to thereby round or chamfer its edge and corner portions.

10 Subsequently, a conductive paste containing Ag and glass is applied to portions of the multilayer body 2 to which the connection end portions 23 to 26 are extended. Then, the conductive paste is baked at a temperature of, for example, about 800 to 820° C. to thereby form an underlying film for each of the terminal electrodes 13 to 16. The underlying film has a thickness of, for example, about 5 μm . Then, for example, a Ni film and a Sn film are formed sequentially on the underlying film by electroplating. The Ni film and the Sn film each have a thickness of, for example, about 3 μm .

15 In this way, the common-mode choke coil 1 illustrated in FIG. 1 is completed.

20 As described above, the common-mode choke coil 1 has the first and second characteristic features. According to the first characteristic feature, the first coil 11 has the path length L1, the second coil 12 has the path length L2, and the sum of the path lengths L1 and L2 is less than or equal to about 3.5 mm. According to the second characteristic feature, each 25 non-conductor layer 3 has a relative permittivity of less than or equal to about 11. These characteristic features help to ensure that at higher frequencies, the common-mode choke coil 1 can transmit differential-mode signals and suppress common-mode noise components. An experiment conducted to verify this is now described below.

30 Exemplary Experiment

To fabricate a green sheet that is to become each non-conductor layer, a glass-ceramic material, a ferrite material, and a burn-out material are prepared as described below.

(1) Glass-Ceramic Material

40 A glass material powder containing 2.0 mass % of K_2O , 20.0 mass % of B_2O_3 , 76.0 mass % of SiO_2 , and 2.0 mass % of Al_2O_3 is prepared.

45 Subsequently, the above-mentioned glass material powder, and quartz and alumina, which are filler components, are weighed in proportions of 63.3 mass %, 34.1 mass %, and 2.6 mass %, respectively, and these weighed materials are put into a ball mill together with pure water, a dispersant, and PSZ media, and then mixed together and pulverized. The resulting mixture is dried to thereby produce a glass-ceramic material powder.

50 (2) Ferrite Material

An oxide raw material is weighed such that Fe_2O_3 , ZnO , and CuO are contained in proportions of 49.0 mol %, 43.0 mol %, and 8.0 mol %, respectively.

55 Subsequently, the weighed material is put into a ball mill together with pure water, a dispersant, and PSZ media, and then mixed together and pulverized. The obtained slurry is dried, and the dried slurry is calcined at a temperature of 800° C. for 2 hours to obtain a ferrite material powder.

60 (3) Burn-Out Material

As a burn-out material, spherical resin balls made of crosslinked polymethylmethacrylate and having a mean particle size of 4 μm are prepared.

65 Subsequently, the glass-ceramic material, the ferrite material, and the burn-out material mentioned above are weighed such that these materials are blended in Materials A to H in the proportions illustrated in Table 1.

11

Subsequently, these weighed materials are put into a ball mill together with an organic binder (polyvinyl butyral-based resin), an organic solvent (ethanol and toluene), and PSZ balls, and then thoroughly mixed together and pulverized.

The obtained slurry is formed into a sheet with a predetermined thickness by a method such as the doctor blade method, and punched into a predetermined size. Green sheets of Materials A to H represented in Table 1 are thus fabricated.

Subsequently, to measure relative permittivity with respect to each of Materials A to H, a predetermined number of the above-mentioned green sheets are stacked such that the thickness after firing will be about 0.5 mm, and the resulting multilayer material is subjected to thermocompression bonding, followed by punching into a disk shape with a diameter of 10 mm.

Subsequently, the disk-shaped multilayer material is fired at a temperature of 900° C. for 2 hours, and an indium-gallium alloy is applied to both surfaces of the resulting sintered body to thereby form electrodes. Samples for relative permittivity measurement are thus obtained.

Subsequently, for each sample mentioned above, electrostatic capacity is measured under the condition that the frequency is 1 MHz and the voltage is 1 Vrms. The relative permittivity (ϵ_r) of each sample is calculated from the diameter and thickness of the sample. The results are illustrated in Table 1.

TABLE 1

Material symbol	Blending proportion (volume %) Glass-ceramic material	ϵ_r Ferrite material	Burn-out material	
A	0	100	—	13.0
B	17	83	—	11.0
C	26	74	—	10.0
D	37	63	—	9.0
E	50	50	—	7.9
F	80	20	—	6.0
G	100	0	—	4.1
H	70	—	30	3.0

Meanwhile, individual common-mode choke coils are fabricated as described below by using the green sheets of Materials A to H illustrated in Table 1 mentioned above.

Laser light is applied to a predetermined portion of a predetermined green sheet among the green sheets including Materials A to H illustrated in Table 1 to thereby provide the predetermined green sheet with a through-hole in which to place a via-conductor. Subsequently, a conductive paste containing Ag is applied to the predetermined green sheet by screen printing. Thus, a via-conductor with the conductive paste filling the above-mentioned through-hole is formed, and a coil including a coil conductor and an extended conductor is formed in a patterned state.

Subsequently, plural green sheets are stacked such that the green sheets are stacked in a predetermined order. The stacked glass-ceramic sheets are then subjected to a warm isotropic press process at a temperature of 80° C. and a pressure of 100 MPa for thermocompression bonding to thereby obtain a multilayer block.

12

Subsequently, the multilayer block is cut with a dicer into individual discrete multilayer structures each dimensioned such that the multilayer structure can become the multilayer body of each individual common-mode choke coil.

Subsequently, each discrete multilayer structure is subjected to rotary barreling to thereby round or chamfer its edge and corner portions.

Subsequently, the discrete multilayer structure is fired in 10 a firing furnace at a temperature of 880° C. for 2 hours to thereby obtain a sintered multilayer body.

Subsequently, a conductive paste containing Ag and glass is applied to a predetermined portion of the outer surface of 15 the multilayer body. The resulting conductive paste is then baked at a temperature of 810° C. for about 1 minute to thereby form an underlying film for each terminal electrode. Then, for example, a Ni film and a Sn film are formed sequentially on the underlying film by electroplating to 20 thereby obtain each terminal electrode.

As described above, common-mode choke coils corresponding to Sample (indicated as "S" in Table 2) 1 to Sample 25 17 are fabricated by varying the following features as illustrated in Table 2: "material used", "1st coil/SG1", "2nd coil/SG2", "1st coil path length/L1", and "2nd coil path length/L2". The multilayer body of the common-mode choke coil corresponding to each sample is dimensioned to have a length dimension L of 0.65 mm, a width dimension W of 0.50 mm, and a height dimension H of 0.30 mm. Each of the first and second coil conductors of the common-mode choke coil corresponding to each sample has a line width of 0.018 mm.

35 Symbols A to H in the "material used" field in Table 2 respectively correspond to symbols A to H illustrated in Table 1. In Table 2, the " ϵ_r " field represents information transferred from the " ϵ_r " field in Table 1. Referring now to 40 FIG. 2, in Table 2, "1st coil/SG1" represents the distance from the first coil conductor 17 of the first coil 11 to each of the lateral face 7, the lateral face 8, and the end face 10 of the multilayer body 2, and "2nd coil/SG2" represents the distance from the second coil conductor 18 of the second coil 12 to each of the lateral face 7, the lateral face 8, the end face 9, and the end face 10 of the multilayer body 2.

Table 2 also illustrates "sum of coil path lengths L1+L2", which is calculated based on the "1st coil path length/L1" 50 and the "2nd coil path length/L2". For Samples 1 to 13 and Samples 15 to 17 in Table 2, the distances SG1 and SG2 are different from each other. Among Samples 1 to 13 and Samples 15 to 17 mentioned above, the absolute value of the 55 difference between the distances SG1 and SG2 is smallest for Samples 11, 12, 13, and 15. In this regard, even for Samples 11, 12, 13, and 15 mentioned above, the absolute value of the difference between the distances SG1 and SG2 is 0.020 mm. Meanwhile, as described above, each of the first 60 coil conductor 17 and the second coil conductor 18 has a line width of 0.018 mm. This means that with respect to Samples 1 to 13 and Samples 15 to 17 for which the distances SG1 and SG2 differ from each other, as illustrated in FIG. 3, there is no overlapping portion between the first coil conductor 17 and the second coil conductor 18 except for a portion where the two coil conductors cross each other.

TABLE 2

S No.	Material used	ϵ_r	1st coil		2nd coil		Sum of coil path lengths	Scc21 transmission characteristic	Sdd21 transmission characteristic			
			SG1 (mm)	SG2 (mm)	1st coil L1 (mm)	2nd coil L2 (mm)			TC at peak position (dB)	TC at 20 GHz (dB)	TC at 30 GHz (dB)	TC at 40 GHz (dB)

For each of the common-mode choke coils corresponding to Samples 1 to 17, the transmission characteristic for common-mode components (Scc21 transmission characteristic) and the transmission characteristic for differential-mode components (Sdd21 transmission characteristic) are obtained.

FIG. 6 and FIG. 7 respectively illustrate the Scc21 transmission characteristic and the Sdd21 transmission characteristic obtained for the common-mode choke coil corresponding to Sample 8 chosen as a representative example.

From the characteristic charts in FIGS. 6 and 7, for Sample 8, the peak position and the transmission coefficient (indicated as "TC" in Table 2) (minimum value) at the peak position are obtained with respect to the Scc21 transmission characteristic, and the respective transmission coefficients at 20 GHz, 30 GHz, and 40 GHz are obtained with respect to the Sdd21 transmission characteristic. Likewise, for each of Samples 1 to 7 and Samples 9 to 17 as well, the peak position and the transmission coefficient (minimum value) at the peak position are obtained with respect to the Scc21 transmission characteristic, and the respective transmission coefficients at 20 GHz, 30 GHz, and 40 GHz are obtained with respect to the Sdd21 transmission characteristic. The results are illustrated in Table 2.

As described above, a cross-section of the common-mode choke coil 1 corresponding to Sample 9 is schematically illustrated in FIG. 5. The interior of the multilayer body 2 of the common-mode choke coil 1 is dotted with a large number of voids 33. The voids 33 are derived from a burn-out material contained in Material H illustrated in Table 1 at a volume fraction of 30%. The voids 33 are left as a result of the burn-out material combusting and burning out in the firing process of the multilayer material mentioned above.

Referring to Table 2, for Samples 1, 3 to 12, and 15 to 17 with the sum of coil path lengths L1+L2 of less than or equal to 3.5 mm and the relative permittivity ϵ_r of non-conductor layers of less than or equal to 11, with respect to the Sdd21 transmission characteristic, the transmission coefficient at 20 GHz can be increased comparatively to greater than or equal to -1.31 dB, the transmission coefficient at 30 GHz can be increased comparatively to greater than or equal to -2.36 dB, and the transmission coefficient at 40 GHz can be

increased comparatively to greater than or equal to -3.09 dB. Thus, attenuation of differential-mode components, which are signal components, can be reduced.

By contrast, for Samples 2, 13, and 14 that do not satisfy the condition that the sum of coil path lengths L1+L2 be less than or equal to 3.5 mm and the relative permittivity ϵ_r of non-conductor layers be less than or equal to 11, with respect to the Sdd21 transmission characteristic, the transmission coefficient at 20 GHz is less than or equal to -1.66 dB, the transmission coefficient at 30 GHz is less than or equal to -2.46 dB, and the transmission coefficient at 40 GHz is less than or equal to -4.14 dB. This indicates that differential-mode components, which are signal components, are subject to large attenuation.

For Samples 1, 3 to 12, and 15 to 17 mentioned above with the sum of coil path lengths L1+L2 of less than or equal to 3.5 mm and the relative permittivity ϵ_r of non-conductor layers of less than or equal to 11, with respect to the Scc21 transmission characteristic, the peak position can be made greater than or equal to 18.7 GHz, and the transmission coefficient at the peak position can be made less than or equal to -20.8 dB. This indicates that these samples allow high-frequency common-mode noise components to be attenuated effectively.

In particular, for Samples 1, 6 to 12, and 15 to 17 with the sum of coil path lengths L1+L2 of less than or equal to 3.5 mm and the relative permittivity ϵ_r of non-conductor layers of less than or equal to 7.9, with respect to the Scc21 transmission characteristic, the peak position can be further shifted higher in frequency to greater than or equal to 22.0 GHz, and the transmission coefficient at the peak position can be further decreased to less than or equal to -22.3 dB. This indicates that these samples allow high-frequency common-mode noise components to be attenuated further effectively.

Further, for Samples 1, 7 to 12, and 15 to 17 with the sum of coil path lengths L1+L2 of less than or equal to 3.5 mm and the relative permittivity ϵ_r of non-conductor layers of less than or equal to 6.0, with respect to the Scc21 transmission characteristic, the peak position can be further shifted higher in frequency, such as to greater than or equal to 24.5 GHz, and the transmission coefficient at the peak position can be further decreased, such as to less than or equal to -24.2 dB.

15

Although the present disclosure has been described above with reference to the illustrated embodiment, various other modifications are possible within the scope of the present disclosure.

For example, in one alternative embodiment, a single coil conductor included in at least one of the first and second coils may be divided in two into a first portion and a second portion, the first portion and the second portion may be disposed respectively along a first interface and a second interface, which are different interfaces between non-conductor layers, and the first portion and the second portion may be connected by a via-conductor. In this case, the path length of the single coil conductor, which constitutes a portion of the coil path length, may be regarded as the path length with the first portion of the coil conductor, the via-conductor, and the second portion of the coil conductor combined.

While preferred embodiments of the disclosure have been described above, it is to be understood that variations and modifications will be apparent to those skilled in the art without departing from the scope and spirit of the disclosure. The scope of the disclosure, therefore, is to be determined solely by the following claims.

What is claimed is:

1. A common-mode choke coil comprising:
a multilayer body including a plurality of non-conductor layers, the plurality of non-conductor layers being stacked and each made of a non-conductor, and the plurality of non-conductor layers including a first plurality of non-conductor layers and a second plurality of non-conductor layers, and the plurality of non-conductor layers each having a relative permittivity of less than or equal to 11;
a first coil and a second coil that are incorporated in the multilayer body, the first coil having a path length L1 and including a first coil conductor disposed along a first interface which is an interface between the first plurality of non-conductor layers, the second coil having a path length L2 and including a second coil conductor disposed along a second interface which is an interface between the second plurality of non-conductor layers and different from the first interface along which the first coil conductor is disposed, and a sum of the path length L1 and the path length L2 being less than or equal to 3.5 mm;
a first terminal electrode and a second terminal electrode that are provided on an outer surface of the multilayer body, the first terminal electrode being electrically connected to a first end, the second terminal electrode being electrically connected to a second end, the first end and the second end being different ends of the first coil; and
a third terminal electrode and a fourth terminal electrode that are provided on an outer surface of the multilayer body, the third terminal electrode being electrically connected to a third end, the fourth terminal electrode being electrically connected to a fourth end, the third end and the fourth end being different ends of the second coil.
2. The common-mode choke coil according to claim 1, wherein
the plurality of non-conductor layers each have a relative permittivity of less than or equal to 7.9.
3. The common-mode choke coil according to claim 2, wherein
the plurality of non-conductor layers each have a relative permittivity of less than or equal to 6.0.

16

4. The common-mode choke coil according to claim 3, wherein
the plurality of non-conductor layers each have a relative permittivity of greater than or equal to 3.0.
5. The common-mode choke coil according to claim 4, wherein
the plurality of non-conductor layers each include a glass-ceramic material.
6. The common-mode choke coil according to claim 3, wherein
the plurality of non-conductor layers each include a glass-ceramic material.
7. The common-mode choke coil according to claim 6, wherein
the plurality of non-conductor layers each include a non-magnetic Zn—Cu ferrite.
8. The common-mode choke coil according to claim 2, wherein
the plurality of non-conductor layers each have a relative permittivity of greater than or equal to 3.0.
9. The common-mode choke coil according to claim 8, wherein
the plurality of non-conductor layers each include a glass-ceramic material.
10. The common-mode choke coil according to claim 2, wherein
the plurality of non-conductor layers each include a glass-ceramic material.
11. The common-mode choke coil according to claim 10, wherein
the plurality of non-conductor layers each include a non-magnetic Zn—Cu ferrite.
12. The common-mode choke coil according to claim 1, wherein
the plurality of non-conductor layers each have a relative permittivity of greater than or equal to 3.0.
13. The common-mode choke coil according to claim 12, wherein
the plurality of non-conductor layers each include a glass-ceramic material.
14. The common-mode choke coil according to claim 13, wherein
the plurality of non-conductor layers each include a non-magnetic Zn—Cu ferrite.
15. The common-mode choke coil according to claim 1, wherein
the plurality of non-conductor layers each include a glass-ceramic material.
16. The common-mode choke coil according to claim 15, wherein
the plurality of non-conductor layers each include a non-magnetic Zn—Cu ferrite.
17. The common-mode choke coil according to claim 15, wherein
the plurality of non-conductor layers each includes a void.
18. The common-mode choke coil according to claim 17, wherein
the plurality of non-conductor layers each includes the void at a volume fraction of less than or equal to 30%.
19. The common-mode choke coil according to claim 1, wherein the path length L1 is the total length of the path from the first end through the first coil conductor to the second end, and the path length L2 is the total length of the path from the third end through the second coil to the fourth end.
20. The common-mode choke coil according to claim 1, wherein the first coil conductor includes a continuously

curved portion positioned directly between the third terminal and the fourth terminal and/or the second coil conductor includes a continuously curved portion positioned directly between the first terminal and the second terminal.
